UNITED STATES PATENT OFFICE

153,601

DESIGN FOR A CROSS

John J. Gresh, Evergreen Park, Ill.

Application March 5, 1947, Serial No. 137,356

Term of patent 14 years

(Cl. D45—15)

To all whom it may concern:

Be it known that I, John J. Gresh, a citizen of the United States, and a resident of Evergreen Park, in the county of Cook and State of Illinois, have invented a new, original, and ornamental Design for a Cross, of which the following is a specification, reference being had to the accompanying drawing, forming part thereof.

In the drawing:

Fig. 1 is a front view of a cross, embodying the new design;
Fig. 2 is a side elevation thereof;
Fig. 3 is a back view;
Fig. 4 is a top view; and
Fig. 5 is a section taken along the line 5—5 of Fig. 1, looking in the direction pointed by the arrows.

I claim:

The ornamental design for a cross, substantially as shown.

JOHN J. GRESH.
